UNITED STATES PATENT OFFICE.

ROBERT A. WEINHARDT, OF CHICAGO, ILLINOIS, ASSIGNEE, BY MESNE ASSIGNMENTS,
TO CONTINENTAL MOTORS CORPORATION, OF DETROIT, MICHIGAN, A CORPORATION
OF VIRGINIA.

MANIFOLD.

1,252,636.

Specification of Letters Patent.

Patented Jan. 8, 1918.

Application filed May 15, 1916. Serial No. 97,549.

To all whom it may concern:

Be it known that I, ROBERT A. WEINHARDT, a citizen of the United States of America, residing at Chicago, in the county of Cook 5 and State of Illinois, have invented certain new and useful Improvements in Manifolds, of which the following is a specification, reference being had therein to the accompanying drawings.

- 10 This invention relates to the arrangement of an intake and exhaust manifold and the inlet and exhaust passages of the cylinder block of a multiple-cylinder explosive engine whereby any condensation of the fuel 15 vapor before it reaches the combustion spaces is prevented and whereby air indrawn into the carburetor is preheated provided the carburetor is located opposite the manifold side of the engine.
- 20 The invention consists in the matters hereinafter set forth, and more particularly pointed out in the appended claims.

Figure 1 is a plan view of a cylinder block with cap removed, together with a manifold, 25 the whole embodying features of the invention;

Fig. 2 is a view in elevation of the manifold and adjacent portions of the cylinder;

Fig. 3 is a view taken on or about the line 30 III—III of Fig. 1, and

Fig. 4 is a view in section taken on or about line IV—IV of Fig. 2, showing stops inserted in the air intake cross-passage.

As herein indicated, a cylinder block having 35 multiple cylinders whose bores are indicated at 1, 2, 3 and 4 respectively, is provided with a transverse passage 5 that may be blocked at each end by suitable stops 6 of any preferred type. Each cylinder has 40 an intake port 8 with inlet passage 9 thereto and an exhaust port 10 with outlet duct 11 therefrom.

A manifold 12 is arranged to be secured 45 against the side of the block with gaskets 13 interposed to insure tight joints. A common intake that registers with the outlet of the passage 5 opens into a fuel duct 16, whereby the indrawn fuel vapor is distributed in either direction equally to the ports 50 8 of the engine through the passages 9. An exhaust duct 14 is in communication through the outlet ducts 11 in the cylinder block with the exhaust ports 9 of the cylinder. Thus the comparatively thin wall or partition 55 15 common to both the inlet passage

and outlet duct is heated by the outgoing gases and thereby any liquid of condensation which falls thereon from the indrawn fuel is quickly revaporized and returned to the going fuel column.

If desired the carburetor can be mounted at the manifold side of the engine, the manifold being arranged as at 17 for such application and suitable opening then being drilled therein. Or suitable and separate 60 intake manifolds may be used. In either case the transverse passage 5 may be stopped off as indicated in Fig. 3, or by means of the gasket 13 as shown in Fig. 1.

As a result of this construction a cylinder 70 block and manifold are obtained that are efficient in preventing condensation, that insure the supply at all times of a thoroughly vaporized charge while the block admits of the mounting of the carburetor on either 75 side.

Obviously, changes in the details of construction may be made without departing from the spirit of my invention and I do not care to limit myself to any particular 80 form or arrangement of parts.

What I claim is:—

1. The combination of a block of multiple cylinders having a transverse passage therethrough and inlet and exhaust ports disposed in sets with the inlet openings above the exhaust openings, with a manifold having an intake passage adapted to form communication between the delivery end of the transverse passage and the intake ports and 85 an exhaust passage below the intake passage adapted to form communication between the cylinder exhaust ports and the main manifold exhaust opening, the division wall between the inlet and outlet passages forming 90 a heating surface for the condensed portion of the indrawn charges that falls thereon.

2. The combination of a block of multiple cylinders provided with a transverse passage 100 between a pair of them and with inlet ports disposed in a plane above a set of outlet ports, with a combined inlet and exhaust manifold having an intake adapted to register with the discharge opening of the transverse passage and a plurality of discharge openings connected to the intake by a passage and adapted to register with the intake port passages of the cylinders, and an exhaust passage below the intake passage, 110

adapted to form a common communication between the various exhaust openings of the cylinders and the manifold discharge opening and a wall forming a heating surface 5 separating the passages.

3. The combination of a block of cylinders cast in multiple with a transverse passage therethrough adapted to be blocked at each end and with exhaust openings from 10 the cylinders leading to the side of the block in a plane below the plane of corresponding inlet openings leading to the intake ports of the cylinders with a manifold adapted to be secured to the cylinder block with an intake 15 passage having an inlet opening adapted to register with the discharge opening of the transverse passage, and a plurality of discharge openings adapted to severally register with the inlet opening passages below 20 the inlet duct of the cylinders and an exhaust passage separated from the inlet duct by a wall forming a heating surface and said passage forming a common communication between the various exhaust openings of 25 the cylinders and the manifold exhaust outlet.

4. The combination of a series of cylin-

ders cast *en bloc* in which a transverse passage is formed between the cylinders, each cylinder being provided with an exhaust discharge outlet from an exhaust port below the plane of an inlet opening to an inlet port, with a combined inlet-and-exhaust manifold having an inlet passage with an intake opening adapted to register with the 30 outlet of the transverse passage and various discharge openings adapted to register severally with the inlet opening to the inlet ports of the cylinder, and with an exhaust passage below the inlet passage having various 35 exhaust inlets adapted to register with the corresponding exhaust outlets of the cylinders and to connect them with the manifold exhaust outlet, the wall between the 40 passages in the manifold forming a heating 45 surface for preventing condensation of fuel vapor passing through the upper inlet passage.

In testimony whereof I affix my signature in presence of two witnesses.

ROBERT A. WEINHARDT.
